THREAD SEPARATING PNEUMATIC THREAD HOLDER AND REMOVER

Richard G. Turner, Worcester, Mass., assignor to
Crompton & Knowles Loom Works, Worcester,
Mass., a corporation of Massachusetts

Application April 1, 1944, Serial No. 529,145

18 Claims. (Cl. 139—247)

This invention relates to improvements in pneumatic thread holders for weft replenishing looms and it is the general object of the invention to provide means by which the waste ends of two different types of threads may be kept separated for the purpose of simplifying reclamation.

In the weaving of certain fabrics it is customary to use two distinctive types of weft, such as rayon, and coarse cotton or woolen yarn. In the interest of economy waste threads which accumulate incident to the weaving operation are saved, but in thread control mechanisms as heretofore made all of the threads have been gathered together and it is a difficult matter to separate them according to their different types.

I have heretofore proposed a pneumatic thread holder and thread remover for the weft ends of reserve bobbins held in the magazine of a weft replenishing loom. It is an important object of the present invention to provide a pneumatic thread holder for each type of thread and collect the threads in different compartments. In this way the process of reclaiming the waste threads is simplified and the previously employed step of separating the threads by hand is eliminated.

Thread holders of the type to which my invention more particularly relates have intake mouths into which a column of air is moved due to the existence of subatmospheric pressures within the holders. Because of this condition there is likelihood that the different types of threads may be drawn into the wrong mouths unless provision is made to keep them separated so that each type of thread will go into its own intake mouth. It is a further object of my present invention to provide a thread holder having multiple intake mouths in conjunction with a separator which will prevent the stream of air moving into one of the intake mouths from attracting threads intended for the other intake mouth.

It is necessary to be able to adjust the location of the intake mouths correctly with respect to the loom lay and magazine in order not only to facilitate partial threading of the shuttle on the first pick after transfer but also effect quick removal of the thread when it is cut at the selvage. It is another object of my invention to construct the thread holders of rigid tubes clamped together and one of which is directly supported by and mounted for angular adjustment on a thread accumulator and the other of which is connected to the accumulator by a flexible tube such as hose. In this way a single adjustment for one of the rigid tubes suffices to place both of the intake mouths in correct position when two thread removers are used.

It is still another object of my present invention to provide a thread accumulator having two or more compartments separated from each other by a wall or the like having a screen which permits pneumatic communication between the compartments but prevents passage of threads from one compartment to the other. The accumulator also has a door which when opened affords access to the thread compartments in the accumulator.

With these and other objects in view which will appear as the description proceeds, my invention resides in the combination and arrangement of parts hereinafter described and set forth.

In the accompanying drawing wherein a convenient embodiment of my invention is set forth,

Fig. 1 is a partial front elevation of a weft replenishing loom having my invention applied thereto.

Fig. 2 is a side elevation of the structure shown in Fig. 1 and looking in the direction of arrow 2 of that figure.

Fig. 3 is an enlarged elevation of the pipe holding claim adjacent to the thread accumulator as shown in Fig. 1.

Fig. 4 is an enlarged vertical section on line 4—4, Fig. 1 and showing the clamp set forth in Fig. 3.

Fig. 5 is an enlarged side elevation of the thread separator shown in the upper part of Fig. 1.

Fig. 6 is a plan view of the structure shown in Fig. 5.

Fig. 7 is an enlarged front elevation of the connection between the thread separator and the support for the magazine, looking in the direction of arrow 7, Fig. 1.

Fig. 8 is an end elevation looking in the direction of arrow 8, Fig. 7, and

Fig. 9 is a vertical section through the thread accumulator taken on line 9—9, Fig. 2.

Referring particularly to Figs. 1 and 2, I have shown a loom frame 10 having a lay 11 which is reciprocated in usual manner by the connectors 12 attached to the top shaft 13 of the loom. The lay is provided with a shuttle box 14 to receive the various shuttles used in the loom. In the present instance the loom is illustrated as adaptable for use with two shuttles, one of which is shown at S. The shuttles are picked back and forth across the loom by mechanism not shown and arrive periodically in the box 14 under a magazine M which in the present instance is provided with front and back stacks of reserve bobbins R and R', respectively. These bobbins have wound thereon wefts of distinctive characteristics, the bobbins R for instance being wound with fine yarn such as rayon, while the bobbins R' are wound with coarse heavier yarn. The bobbins have weft ends extending from them,

the front group of fine weft ends corresponding to the bobbins R being indicated at W, and the rear group of coarse weft ends corresponding to bobbins R' being indicated at W'.

Mechanism well known but not shown causes transfer of a bobbin from one or another of the groups in the magazine into the corresponding shuttle when the latter is depleted and in box 14. During subsequent picking of the shuttle its weft end is held at a thread holder designated generally at H to effect partial threading of the shuttle, and on some subsequent pick of the loom this thread is cut at the selvage by mechanism not shown but well understood. The thread is then waste and should be removed from the loom.

In carrying my present invention into effect I provide means for leading the waste weft ends from the groups W and W' to separate compartments C and C' in a thread accumulator A. The accumulator is mounted on a bracket 20 secured to the loomside and is formed as a box-like structure indicated in Figs. 1, 2 and 9. A bobbin can 21 rests on top of the accumulator in position to receive the outgoing or exhausted bobbins as they move downwardly from the depleted shuttle along the lay carried bobbin chute 22.

The accumulator has inner and outer side walls 25 and 26, respectively, front and back walls 27 and 28, respectively, and has a top 29 and a bottom 30. The front wall is provided with an aperture 31 normally closed by a door 32 which is preferably transparent and hinged at 33 to the wall 27. This door may be located centrally of the front wall as indicated in Fig. 1, and can be raised to afford access to the threads within the accumulator compartments.

A vertical wall 35 extending between the front and back walls of the accumulator divides the latter into the compartments C and C'. This wall or partition has an aperture 36 which is covered by a screen 37 of such mesh as will prevent threads from passing from one compartment to the other, but will afford pneumatic communication between the two compartments. This wall extends forwardly and engages or at least lies very close to the door when the latter is closed.

In order to insure operation of the invention it is necessary to maintain subatmospheric pressures within both compartments C and C', and in order to effect this result I provide a pipe 40 attached by a fitting 41 to the back wall 28 of the accumulator. The fitting is so constructed that it affords pneumatic communication between the interior of the pipe and compartment C. Pipe 40 is connected to any mechanism which will create subatmospheric pressures and during operation of the loom there is a stream of air moving rearwardly either intermittently or continuously within pipe 40 in the direction of arrow a, Fig. 2.

The thread holder is constructed of front and back rigid tubes 45 and 46, respectively, the first of these tubes being connected by a fitting 47 to the outer wall 26 of the accumulator. Fitting 47 is so constructed that the interior of pipe or tube 45 is pneumatically connected to compartment C. The fitting 47 is held to wall 26 by means of bolts 48 tapped into wall 26 and passing through slots 49 which permit an angular adjustment of the fitting and therefore of the pipe 45 with respect to the accumulator A.

The bottom of the other pipe 46 is connected to a flexible tube 50 which extends to a fitting

51 secured to the bottom of the accumulator. Fitting 51 is so constructed and located as to afford pneumatic communication between tube 50 and compartment C'.

5 The two rigid pipes 45 and 46 are held together by clamp means shown in detail in Figs. 3 to 6. The lower clamp 55, as shown in Figs. 3 and 4, is formed of two plates 56 and 57 held together by bolts 58. A rib 59 on each of the plates extends into the space between the pipes 45 and 46 and the latter are held together by tightening the bolts 58 as will be apparent from Figs. 3 and 4. This clamp can be slid along the pipes 45 and 46 to any desired adjusted position and then tightened.

10 The upper clamp 60 is formed of top and bottom plates 61 and 62, respectively, held together by bolts 63, as shown in Figs. 5 and 6. These two clamps 55 and 60 therefore afford means 20 for clamping the pipes 45 and 46 together so that they move in unison when an adjustment of pipe 45 is made with respect to the accumulator. During this adjustment the flexible tube or hose 25 will bend sufficiently to accommodate the movement of pipe 45. This adjustment may be necessary to locate the thread holder H correctly in the loom.

25 The pipes 45 and 46 have their upper ends open to provide intake mouths 65 and 66, respectively, which face toward the center of the loom, or to the left as viewed in Fig. 1. Mouth 65 is intended for reception of the forward group of threads W, while the other mouth 66 receives the group of threads W'. During operation of 30 the loom streams of air move into the intake mouths and in order to prevent the threads of each group from being drawn into the intake mouth corresponding to the other group I provide separator means shown particularly in Figs. 1, 5 and 6.

35 The separator means comprises a plate 70 of thin section and extending vertically above and below the intake mouths and also extending inwardly toward the magazine. This plate 70 may conveniently be formed as a part of the top clamp plate 61 and serves as a baffle to separate the two streams of air which move into the intake mouths.

40 In order that the upper ends of the pipes 45 and 46 and plate 70 may be prevented from undue vibration I provide means for supporting them relatively to a fixed part of the loom. The magazine includes in its construction a stud 75 mounted on a fixed stand 76 which is supported by the loom frame. Stud 75 extends outwardly beyond the end of the magazine and has a collar 77 secured thereto by bolt 78. The collar may have a part thereof split to provide front and back arms 79 and 80, respectively, which receive the upper end of a brace 81 held to the collar by bolt 78. Another bolt 82 secures the lower end of brace 81 to the plate 70. The latter as well as the pipes 45 and 46 are thus held against undue vibration during loom operation. When angular 45 adjustments are made at the fitting 47 the brace 81 may be bent slightly or the collar 77 released by loosening of bolt 78 to take a new setting, after which the bolt 78 is tightened. It is to be understood that the bolt 78 when tightened 50 serves to clamp the collar 77 on the stud 75.

45 In the operation of the loom, the two shuttles, only one of which is shown herein, enter the box 14 one at a time. These shuttles carry two different kinds of weft, one of which may be fine, such as rayon, and the other of which may be

coarse, such as heavy cotton. When a shuttle in box 14 is depleted it will be replenished by a bobbin drawn from the corresponding magazine stack. In the present instance it is assumed that shuttle S will be replenished from the front stack having bobbins R of fine weft. When the other shuttle is replenished it will receive a bobbin R' wound with coarse weft and drawn from the rear stack of the magazine.

At some time subsequent to replenishment the thread of the newly inserted bobbin will be cut at the selvage and be drawn into the associated intake mouth and drawn downwardly by sub-atmospheric pressure into the corresponding compartment. Thus, the thread from shuttle S may be assumed to extend into the intake mouth 65 and extend down through pipe 45 through fitting 47 into compartment C. In similar manner the thread from the other shuttle will enter intake mouth 66 and pass down pipe 46 and hose 50 and through the fitting 51 into the compartment C'. It is to be understood that subatmospheric pressures will exist within both the compartments C and C' because of the screen 37. During this operation the door 32 is closed, but when a large mass of threads accumulate within the compartments the door is opened and the threads removed. Since the different types of threads have been led to their respective compartments the waste yarns are separated and the previous labor of manual separation is eliminated. It will be apparent from Fig. 1 that access to both of the compartments C and C' is afforded when the door 32 is opened.

When new bobbins are placed in the magazine their weft ends will be held manually in front of the corresponding intake mouth and be drawn into the latter pneumatically. During this filling of the magazine the plate 70 prevents the weft ends of the bobbins from entering the wrong intake mouth.

From the foregoing it will be seen that I have provided simple means for separating the waste weft ends of a loom operating with two distinctive types of weft. This separation is effected by means of two pneumatic units each having a thread holder with an intake mouth and a thread compartment for the corresponding type of thread. It will also be seen that the plate 70 serves as a separator to prevent the threads from entering the wrong intake mouths, and that the separator is so constructed that it may cooperate with the brace 81 and also the clamp 60 to prevent vibration of the upper ends of the pipes 45 and 46. Furthermore, the adjustment of fitting 47 for changing the angular position of pipe 45 with respect to the accumulator will be accompanied by a slight bending of the hose or flexible tube 50. It will also be noted that the accumulator is constructed in such a manner that opening of the door 32 affords access to both of the compartments C and C'. Also, the screen 37 on wall or partition 35 prevents threads from passing from one compartment to the other but affords pneumatic communication between the compartments.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom having two groups of weft threads, a pair of pneumatic thread removers each having an intake mouth,

each of said intake mouths receiving one of said groups of threads, a pair of hollow thread accumulators in each of which subatmospheric pressures exist, one accumulator for each of said removers, each intake mouth being pneumatically connected to the interior of the corresponding accumulator and having a stream of air moving thereinto, and a separator between said mouths to prevent the stream of air moving into each mouth from attracting the threads corresponding to the other mouth.

2. In a weft replenishing loom having two groups of weft threads, a thread holding, removing and accumulating unit for each group, each unit having an intake mouth for the corresponding group pneumatically connected to the interior of a hollow accumulator within which subatmospheric pressures exist, and a separator between said mouths to prevent the group corresponding to each mouth from moving into the other mouth.

3. In a weft replenishing loom having two groups of weft threads, a thread holding, removing and accumulating unit for each group, each unit having an intake mouth for the corresponding group pneumatically connected to the interior of a hollow accumulator within which subatmospheric pressures exist, and means to prevent the group corresponding to each mouth from moving into the other mouth.

4. In a weft replenishing loom having two groups of weft threads, a thread holding, removing and accumulating unit for each group, each unit having an intake mouth for the corresponding group pneumatically connected to the interior of a hollow accumulator within which subatmospheric pressures exist, and means extending above and below and between said intake mouths to prevent the threads of each group from moving into the intake mouth corresponding to the other group of threads.

5. In a weft replenishing mechanism having reserve bobbins from which extend two groups of weft threads, a thread holding, removing and accumulating unit for each group of threads, each unit having an intake mouth receiving the threads of the corresponding group and communicating pneumatically with the interior of a hollow thread accumulator within which subatmospheric pressures exist, and means extending from said mouths toward said reserve bobbins and separating said groups.

6. In a weft replenishing mechanism having reserve bobbins from which extend two groups of weft threads, a thread holding, removing and accumulating unit for each group of threads, each unit having an intake mouth receiving the threads of the corresponding group and communicating pneumatically with the interior of a hollow thread accumulator within which subatmospheric pressures exist, and a separator for said groups of threads between said mouths extending toward said replenishing mechanism and preventing the threads of each group from entering the intake mouth corresponding to the other group of threads.

7. In a weft replenishing mechanism having reserve bobbins from which extend two groups of weft threads, a thread holding, removing and accumulating unit for each group of threads, each unit having an intake mouth receiving the threads of the corresponding group and communicating pneumatically with the interior of a hollow thread accumulator within which subatmospheric pressures exist, said intake mouths

being closely adjacent to each other, and a separator for said groups of threads extending from said mouths toward said replenishing mechanism and preventing the threads of each group from entering the mouth corresponding to the other group.

8. In a weft replenishing mechanism having reserve bobbins from which extend two groups of weft threads, a thread holding, removing and accumulating unit for each group of threads, each unit comprising a tube communicating with the interior of a hollow thread accumulator within which subatmospheric pressures exist and each tube having an intake mouth receiving the corresponding group of threads, a clamp holding the ends of the tubes together adjacent to their intake mouths, and a separator for said group connected to said clamp and extending between said mouths and preventing the threads of each group from entering the mouth corresponding to the other group of threads.

9. In a weft replenishing mechanism having reserve bobbins from which extend two groups of weft threads, a thread holding, removing and accumulating unit for each group of threads, each unit comprising a tube communicating with the interior of a hollow thread accumulator within which subatmospheric pressures exist and each tube having an intake mouth receiving the corresponding group of threads, means connecting said tubes adjacent to the intake mouths thereof, and a separator for said groups supported by said means and extending between said mouths and preventing the threads of each group from entering the mouth corresponding to the other group.

10. In a weft replenishing mechanism having reserve bobbins from which extend two groups of weft threads, a thread holding, removing and accumulating unit for each group of threads, each unit comprising a tube communicating with the interior of a hollow thread accumulator within which subatmospheric pressures exist and each tube having an intake mouth receiving the corresponding group of threads, means supported by and connecting said tubes and holding the intake mouths thereof closely adjacent to each other, and a separator for said groups supported by said means and extending between said mouths and preventing the threads of each group from entering the mouth corresponding to the other group.

11. In a weft replenishing loom having two groups of weft threads and a thread accumulator formed with two thread compartments, a pair of rigid tubes connected at their upper ends and having intake mouths for said threads, one mouth for each group of threads, means connecting one of said rigid tubes to said accumulator for angular adjustment relatively thereto and providing pneumatic communication between said one tube and one of said thread compartments, and a flexible tube connecting the other rigid tube pneumatically with the other compartment.

12. In a weft replenishing loom having two groups of weft threads and a thread accumulator formed with two thread compartments, a pair of rigid tubes connected at their upper ends and having intake mouths for said threads, one mouth for each group of threads, a fitting on said accumulator secured to and connecting one of said tubes pneumatically with one of said compartments, means to hold said fitting and one tube in adjusted angular position relatively to said

75 accumulator, and a flexible tube connecting the other rigid tube pneumatically with the other of said compartments.

13. In a weft replenishing loom having two groups of weft threads and a thread accumulator formed with two thread compartments, a pair of rigid tubes connected at their upper ends and having intake mouths for said threads, one mouth for each group of threads, a fitting on said accumulator secured to and connecting one of said tubes pneumatically with one of said compartments, means to hold said fitting and one tube in adjusted angular position relatively to said accumulator, a second fitting on said accumulator adjacent to the other compartment, and a flexible tube connecting the other rigid tube to said second fitting, the latter and said flexible tube connecting said other rigid tube pneumatically with said other compartment.

14. In a thread accumulator for a weft replenishing loom having two groups of weft ends and a pneumatic thread holder and remover unit for each group, means connected to the accumulator through which subatmospheric pressures are created within the accumulator, a partition in said accumulator forming two thread compartments therein, means in said partition preventing threads from passing from one compartment to the other compartment but establishing 25 pneumatic connection between said compartments, and means connecting each compartment pneumatically with one of said units.

15. A weft replenishing loom waste thread accumulator having two thread compartments connected by means preventing threads from passing from one compartment to the other compartment but pneumatically connecting said compartments, each compartment having a thread inlet, and the accumulator having means 40 through which subatmospheric pressures may be created within said compartments.

16. In a thread accumulator for a weft replenishing loom, a hollow structure having a front wall provided with an aperture, a partition within said structure dividing the accumulator into two thread compartments, said partition extending across said aperture, a thread inlet for each compartment, means through which subatmospheric pressures may be created 50 within said compartments, and a door normally closing said aperture but when open affording access to both of said compartments.

17. In a thread accumulator for a weft replenishing loom, a hollow structure having a front wall provided with an aperture, a partition within said structure dividing the accumulator into two thread compartments, and located to afford access through said aperture to both of said compartments, a thread inlet for each compartment, and a door normally closing said aperture and when open affording access to both compartments through said aperture.

18. In a thread accumulator to collect separately the threads from two groups of threads in a weft replenishing loom, a pneumatic thread holder and remover unit for each group of threads, means comprising two thread accumulating compartments, one compartment for each unit, means pneumatically connecting each unit with the corresponding compartment, and means pneumatically connected to both of said compartments to create subatmospheric pressures therein.
